Primary Examiner—Nanda Bondade*(74) Attorney, Agent, or Firm*—Rader, Fishman & Grauer PLLC(57) **CLAIM**

The ornamental design for a disc player, as shown and described.

DESCRIPTION

FIG. 1 is a front elevational view of a disc player showing my new design;

FIG. 2 is a top plan view thereof; and,

FIG. 3 is a bottom plan view thereof.

The even broken line showings of an optical disc player in FIGS. 1-3 are for illustrative purpose only and form no part of the claimed design. The dot-dash broken lines in FIGS. 1-3 define, but are not included in, the boundaries of the claimed design.
